UNITED STATES PATENT OFFICE.

IRVING R. ALLEN, OF CHICAGO, ILLINOIS, ASSIGNOR TO ROBERTS CONE MANUFACTURING COMPANY, OF ST. JOSEPH, MISSOURI, A CORPORATION OF MISSOURI.

DESIGN FOR AN ICE-CREAM CONE.

56,576.

Specification for Design.

Patented Nov. 16, 1920.

Application filed January 8, 1920. Serial No. 350,225. Term of patent 14 years.

To all whom it may concern:

Be it known that I, IRVING R. ALLEN, a citizen of the United States of America, residing at Chicago, in the county of Cook and State of Illinois, have invented a new, original, and ornamental Design for Ice-Cream Cones, of which the following is a specification, reference being had to the accompanying drawing, forming part thereof.

In the drawing,
The figure is a perspective view of an ice cream cone, showing my new design.

I claim:
The ornamental design for an ice cream cone, as shown.

IRVING R. ALLEN.
